AUTOMATIC FUEL VAPORIZER AND AUXILIARY FUEL SUPPLY FOR INTERNAL COMBUSTION ENGINES

Irven E. Coffey, Pine Lawn, Mo.

Application January 28, 1932, Serial No. 589,436
Renewed January 9, 1937

4 Claims. (Cl. 123—119)

My invention relates to an improvement in the fuel supply for an internal combustion engine for the initial starting of a cold engine, and applies to the type in which a liquid fuel is vaporized or gasified before entering the engine cylinders.

In the present practice of starting cold engines an electric starting motor is used to rotate the crank shaft and reciprocate the pistons for creating a suction to draw fuel into such cylinders from the carburetor. In order to increase the flow of fuel it is usually the practice to use a choke on the air intake which functions to increase, to a great extent, the amount of liquid fuel in proportion to the air. Usually this fuel is not properly vaporized in the cold intake manifold and a considerable proportion condenses in the manifold. Also, the fuel is in the form of a liquid vapor instead of gas enters the cylinder. When the gas becomes ignited and drives the engine to the release of the starting motor, the condensed fuel is drawn into the engine, and as it is commonly necessary to maintain the choke more or less closed until the engine becomes warmed, the fuel enters the cylinders in the form of a vapor instead of a dry gas, which vapors, especially when gasoline fuel is used, wash the lubricating oil from the cylinder walls and pass by the cylinders, diluting the crank case lubricating oil. Attempts have been made to remedy this defect by installation of electric heating elements in the intake manifold but it is necessary to heat a large proportion of air compared with the amount of vaporized fuel; therefore, these heaters are inefficient. Attempts have also been made to have an automatically actuated choke but this also has a disadvantage that it always functions even if through inadvertence the ignition switch is not turned to the closed circuit position, in which case the engine usually becomes flooded with the condensed fuel.

A main object and feature of my invention is at the same time the starting motor is energized to turn over the engine for starting, to inject an auxiliary supply of fuel, preferably from the carburetor into the intake manifold, and to heat this fuel as it is atomized and vaporized, the heating preferably being done by an electrical heating element. In addition, I provide an auxiliary air supply which functions to carry the fuel which is gasified by heat, and thus provide a dry gas with heated air for the initial starting of the engine.

After the engine has been initially started and the starting motor no longer functions, and also

the electrical heat is discontinued, I provide an auxiliary fuel supply with additional air to carry such vaporized and gasified fuel. This forms a secondary object and feature of my invention.

A third feature of my invention is the provision of a thermostatic control for the secondary auxiliary supply whereby when the engine becomes sufficiently hot to draw the fuel from the carburetor in a normal manner, the auxiliary fuel supply and the auxiliary air is cut off and maintained in a cut off condition while the engine is running at its normal operating temperatures. However, the thermostatic control is operative that should the engine cool to such an extent as to possibly make the starting difficult, the auxiliary fuel supply will come into operation with the auxiliary air to carry such supply, and on use of the starting motor electrical heat will be supplied to the auxiliary fuel and auxiliary air. In one form of my invention the hot gasified fuel is fed without the auxiliary air direct into the intake manifold.

An important feature of my invention is that if the engine is at a sufficient temperature to operate directly from the fuel drawn through the carburetor on starting, although the electric heating element will be automatically heated, there will be no auxiliary gas or air supply drawn through the heating device.

The operations of my invention may be accomplished in various forms of appliances which may be installed on engines now in use or may be built into new installations.

In the preferred form of my invention I may employ a piston operating directly as an auxiliary fuel pump, this piston having a diaphragm which is subject to atmospheric air pressure and also to a moderate suction of the engine. With this arrangement the auxiliary fuel and air supply device is placed in the cylinder in which the piston operates in a position to be always in a normal cold position filled with the fuel, the device preferably being arranged at substantially the level of the fuel in the carburetor. A piston or pump plunger operates in this cylinder which is filled with the fuel. A diaphragm is connected to the piston and above the diaphragm there is an auxiliary air connection. The piston carries one element of a needle valve, preferably the seat, the needle being stationary and adjustable. Above the needle valve there is an electrical heating unit, and above this unit a connection to the intake manifold, preferably below the throttle valve. With this arrangement, on energizing the starting motor, the solenoid pulls downward-

ly on the piston, the action being to force the liquid fuel below the piston upwardly through the needle valve and inject this into an auxiliary stream of air and subject the air and the fuel to the electric heating unit. The dry vaporized gas thus formed passes through the intake manifold to the cylinders of the engine. In this construction, also, I provide a thermostatic control for the auxiliary air, this supply being normally open when the engine is cold, but as the auxiliary air supply becomes heated and the engine heated, the auxiliary supply is shut off. On shutting off of the air supply the fuel supply through the needle valve is stopped. Therefore, when the engine runs sufficiently hot to draw fuel from the carburetor, my device is inoperative to supply auxiliary fuel and auxiliary air, but when the engine is cold and while it is warming up, first the auxiliary fuel heated to form a dry gas is supplied and then an auxiliary fuel without being heated is supplied, unless the heating circuit is closed.

In another form of my invention I utilize a piston operating in a cylinder. This piston is normally held in an inoperative position by counterbalanced spring. The piston is under the influence of a solenoid which is connected into the starting motor circuit, preferably as a parallel circuit so that on energizing of the starting motor the solenoid is energized to shift the piston. At the same time an electric heating unit also in circuit with the solenoid is energized to provide electrical heat. The suction caused by the turning of the engine by the starting motor draws the liquid fuel preferably from the carburetor through a needle valve controlled by and preferably built into the piston. As the fuel passes through this valve, it is atomized and immediately subjected to the hot electrical heating unit. In this case when the engine is cold there is no auxiliary air supply but the hot gasified fuel is injected directly into the intake manifold and mixed with the inflowing air through the carburetor. The secondary fuel supply continues to function after the starting motor circuit is open by the engine operating under its own power unless the suction is sufficient at this stage to close the needle valve.

In the second form of my invention above described in which the liquid fuel is subjected to the electric heating element and thus discharged into the intake manifold as the hot dry gas, the suction for bringing the fuel to the needle valve is created by the suction in the manifold. An auxiliary air supply is provided but when the engine is cold this is cut off by a thermostatic control. However, as the engine becomes heated, the auxiliary air, which is preferably heated by the exhaust manifold, operates the thermostatic control to open the air supply to the needle valve, which breaks the vacuum and stops the suction of the fuel or materially lessens the flow of such fuel. After the engine is running and the thermostatic control heated, the auxiliary air valves are wide open and will function to add a slight additional amount of air to the intake manifold, but as the suction on this manifold tends to close the needle valve, there is an automatic regulation of this additional air supply. Such supply, however, is insufficient to interfere with the normal operation of the engine.

A main characteristic in my invention in any of its forms is that the closing of the starting motor circuit operates the solenoid to provide

the additional fuel supply and at the same time this fuel supply is heated and forms a dry gas. Therefore, the closing of the starting motor switch performs two functions of energizing the starter and providing a heated dry gas for the initial starting of the engine. My invention comprehends that instead of using the starting motor switch to energize the solenoid and the electric heating coil I may use an entirely separate switch devoted solely for this purpose, or utilize the ignition switch of the ignition circuit. I also contemplate having the solenoid and the heating circuits either in series or parallel with a common switch, or a separate switch may be utilized for either feature, thus having these circuits independent.

My invention is illustrated in connection with the accompanying drawings, in which:

Fig. 1 is a diagrammatic illustration of the fuel supply and starting system of the engine 20 with my auxiliary fuel device illustrated in elevation;

Fig. 2 is a vertical section through my auxiliary fuel device;

Fig. 3 is a detail horizontal section on the line 3—3 of Fig. 2 in the direction of the arrows;

Fig. 4 is a detail horizontal section on the line 4—4 of Fig. 2 in the direction of the arrows;

Fig. 5 is a diagrammatic illustration of another 30 adaptation of my invention;

Fig. 6 is a vertical section through the alternative form of my invention illustrated in Fig. 5;

Fig. 7 is an enlarged vertical section of the piston, needle valve, and air control;

Fig. 8 is a detail horizontal section on the line 8—8 of Fig. 7 in the direction of the arrows;

Fig. 9 is a detail horizontal section on the line 9—9 of Fig. 7 in the direction of the arrows.

Referring first to the illustration of Fig. 1, the engine block with the engine cylinders is indicated by the numeral 11, the intake manifold 12, the exhaust manifold by 13, the carburetor by 14, such carburetor being indicated as having a choke valve 15 and a throttle valve 16, these latter being of conventional type. While the carburetor is illustrated as of the up draft type, my invention applies equally to a down draft type of carburetor.

The starting system indicates a starting motor 17 and a starting switch 18. This is illustrated as having a bridging piece 19 which connects to the contact points 20 and 21. The contact 20 is indicated as having a lead 22 to the storage battery 23, such being a source of supply, the negative side of this battery being grounded at 24. The contact 21 has a lead 25 to the terminal 26 of the starting motor.

Referring particularly to the device of my invention shown in detail in Figs. 2, 3, and 4, I employ a casing structure 27 which may be attached to the engine block in any suitable manner or, if desired, supported from the carburetor. This has a cylinder 28 therein which is preferably made of brass. A closure plug 29 is screwed into the lower end of the cylinder and has a packing gasket 30 engaging the case and forming a liquid-tight seal. A fuel supply pipe 31 is connected to a nipple 32 at the lower end of the plug. This plug is provided with a check valve 33, such valve being formed by utilizing a large bore 34. A tube 35 is threaded into this bore and has a valve seat 36 on which a ball check valve 37 is seated. A pin 38 limits the upward movement of this ball. A small bore 75

39 leads through the upper end of the plug into the fuel chamber 40.

The fuel pump comprises a loose fitting cylinder or plunger 41 preferably having a number 5 of vertical grooves 42. This has a recess 43 at the bottom and is urged upwardly by a compression spring 44 seated in this recess and bearing on the plug 29. A diaphragm 45 is attached at its periphery to the connecting flanges 46 of the case, 10 the case thus having a lower and an upper section. The center portion of the diaphragm bears on a shoulder 47 on a piston or plunger 41. A threaded nut 48 threaded on the plug 49 clamps the center portion of the diaphragm and this is 15 held by a lock nut 50. The nut 48 has a plurality of outwardly projecting fingers 51. The cylinder or plunger 41 has a fuel duct 52, which duct is carried upwardly by an upwardly extending small fuel tube 53, this arising above the plug 49, and is 20 provided with a valve seat 54 forming a needle valve as hereinunder detailed.

The casing 27 has a cylindrical upwardly projecting portion 55 with a tube 56 extending thereabove. This tube has a head 57 in which is 25 threaded the plug 58 to which is connected the stem 59 of the needle 60, which forms the needle valve operating in connection with the needle valve seat 54. A knurled head 61 allows adjustment of the stem and, hence, of the needle in 30 preference to the needle valve seat. A nipple 62 is connected to the tube 56 and to this nipple there is a fuel pipe 63 which leads to the intake manifold 64, preferably below the throttle valve indicated 16.

35 The air supply employs an intake air pipe 65 which has a heating coil 66 surrounding the exhaust manifold. This pipe has an open end exposed to atmosphere. A rotary air valve designated by the assembly numeral 67 is constructed 40 in the upwardly projecting portion 55 of the case. This has a cylindrical wall 68, a bottom closure plate 69, a top plate 70, this having a sleeve 71 through which the stem 59 of the needle extends. The top is provided with a series of ports 72 which 45 are adapted to register with ports 73 in the closed top 74 of the upwardly projecting portion 55 of the case. The side wall 68 is provided with a plurality of circumferential slots 75, through which extend stop screws 76. These screws limit the 50 rotation of the valve and also support the valve in the upwardly projecting portion 55 of the case. The bottom 69 of the valve is provided with an opening 77 from which extends upwardly a tube 78, which tube has an inturned flange end 79, there 55 being a small annular opening 80 between this flange and the tube 53 which carries the seat of the needle valve.

The electrical system employs a solenoid 81, the winding of which is indicated as being on 60 the outside of the cylinder 28 in the lower portion of the case 27. An electrical heating coil 82 is mounted in the air valve 67. There is illustrated a terminal 83 which extends through the cylindrical wall 68. The lower end of the heating coil 65 is connected to this terminal at 84 and the upper end is connected to the sleeve 71 at 85. Thus, the heating coil may rotate with the air valve housing. The thermostatic control is by 70 means of a bi-metallic thermostatic strip 86, which is arranged in the form of a spiral, one end being connected at 87 to the insulated terminal 83 on the outside of the valve 67. The opposite end has an outwardly bent finger 88 which operates between the contact 89 of electric terminal 75 90, which terminal extends through the wall of

the case 27. A stop 81 on this wall limits the movement of the free outer end of the thermostatic strip. I employ an electric lead 92 which is illustrated as connected to a selector switch 92' connecting to a source of power and ground. The solenoid has a first terminal 93 to which the lead 92 connects, and a second terminal 94, this extending through the case 27, and an electrical lead 95 connects to the terminal 90.

In my invention the chamber below the diaphragm designated 96 may be considered with the chamber 40 as the fuel chamber because the device is installed at substantially the level of the fuel in the carburetor so that the fuel seeking its own level will rise past the check valve 33 and 10 into the fuel duct 52. The arrangement, however, must be such that the needle valve seat 54 is never below the level at which the fuel would rise in the auxiliary fuel device when the liquid 15 seeks its own level. The upper part of the chamber 97 above the diaphragm may be considered as the air chamber. 20

The manner of operation and functioning of my device is substantially as follows:

When the selector switch 92' is closed, the current flow is by lead 92 to terminal 93, solenoid winding 81, terminal 94, lead 95, terminal 90 to 25 89 through closed contact 88 to thermostat coil 86 when this is cold, through terminal 84 to heating element 82 and ground at 85. The current through thermostat 86 heats and expands this, which, together with the heated air drawn from around the exhaust manifold at 66 through pipe 65 causes the thermostat to actuate the air 30 valve 67 and also to open contact at 88. 35

Presuming the engine is cold, the compression spring 44 maintains the combination piston and plunger 41 in an elevated position, the limit to movement being by the fingers 51 engaging the bottom plate 69 of the rotatable air valve 67. 40 When in this position the stem of the needle valve is adjusted so that the needle valve is closed or substantially closed and in this position the ports 72 and 73 are in registry. The thermostatic strip is cold so that the free end 88 is in contact with 45 the contact point 89 of the terminal 90. In this position the chamber 40 below the plunger 41 and the chamber 96 below the diaphragm are filled with liquid fuel.

When the starting switches are actuated to the 50 closed circuit position, a circuit is closed to the starting motor which rotates the crank shaft and reciprocates the pistons and to the ignition circuit is also closed. At the same instant the solenoid 81 is energized and a current is conducted 55 through the bi-metallic thermostatic strips to the heating coil 82, which is designed to substantially instantly become hot. The solenoid exerts an attraction on the cylinder or plunger 41 which functions as the armature of the solenoid 60 and draws this downwardly, this action also pulling down on the diaphragm, causing this portion of the device to operate as a pump and force the liquid fuel in the chambers 40 and 96 upwardly 65 through the liquid duct 52 and through the 65 needle valve at the top of the tube 53 where the fine atomized fuel immediately comes into contact with the heating coil 82. As the pistons are reciprocating they create a suction in the intake manifold but as the auxiliary fuel pipe 63 is connected below the throttle valve, that is, on the carburetor side of such valve, there is but a slight suction. This, however, is sufficient to draw atmospheric air through the air pipe 65 into the chamber 97 above the diaphragm. This air 70 75

blows upwardly through the annular opening 80 surrounding the needle valve, causing an immediate mixture of the air and the fuel, both being subjected to the heating action of the heating coil. This heating action immediately changes the atomized liquid fuel into a dry gas which is drawn through the intake manifold into the engine cylinders. This action takes place without the closing of the choke valve 15.

10 The secondary action of my device is after the engine is started and the starting switch 18 is opened, in which case the solenoid is deenergized, as is also the heating coil. The spring 44 then forces the piston or plunger upwardly but, 15 as above mentioned, when this is in its upper position the needle valve is partly opened. The auxiliary air with a reduced amount of liquid fuel is then drawn by suction through the ports 72 and 73, which are open, and the fuel pipe 63 20 into the intake manifold. This gas is not automatically heated, however. At the same time the engine draws fuel directly from the carburetor and the exhaust manifold becomes heated, and by means of the heating coil 66 heats the air 25 through the pipe 65. As the air becomes heated in the chamber 97 the thermostatic strip 86 is heated and expands so that the free end 88 moves from the contact end 89 of the terminal 90 and abuts against the stop 91. The further expansion 30 of the thermostatic strip then causes the rotation of the valve 67, bringing the ports 72 and 73 out of registry and stopping the upward flow of air and vaporized fuel. In addition, the conduction of heat from the engine block tends 35 to heat the thermostatic strip so that as long as the engine is running normally and drawing fuel from the carburetor with the engine hot, the ports 72 and 73 are maintained out of registry and thus the valve 67 closed.

40 Should the engine stop and be started while the engine is still hot and the thermostatic strip 86 still hot, the circuit is broken at 88 and 91, hence, neither the solenoid nor the heating coil is energized and no auxiliary fuel fed to the engine.

45 In the construction illustrated in Figs. 5 through 9, the air valve control device designated generally by the numeral 100 employs a cylinder 101 at the upper end of which there is a solenoid 102, the windings being indicated, and outside of 50 this solenoid there is a cover or case 103. A closure head 104 is secured to the top of the case, and in a large recess 105 there is threaded a tubular plug 106. This plug has a nipple 107 to which is connected a gasoline feed tube 108, this tube being indicated as connected to the carburetor at the base thereof at 109. A bottom closure 110 is connected to the lower end of the case 103 and connects to the cylinder 101. A sleeve 111 is fitted on the lower portion of the cylinder and is 55 retained in position by a ring 112 secured to the lower end of the cylinder 101. A piston 113 (note Fig. 7) slides in the cylinder 101. This piston has a downwardly projecting portion 114. A relatively small bore 115 extends upwardly 60 through the portion 114 of the piston and there is a relatively large bore 116 at the top or at the piston proper. A fixed fuel and air tube 117 extends through the bores 115 and 116 rising to a considerable height above the piston, and this is 65 retained in place by a screw threaded connection 118 with the lower part of the bore. The tube has a head 119 with wrench kerfs 120 and a downwardly extending sleeve 121.

The air control is by means of a rotatable sleeve 122 which is fitted over the upper end of

the tube 117, this sleeve being contracted at the upper end 123 with an inwardly turned flange. At the lower end of the sleeve there is a cup 124 with an upwardly extending flange 125. This flange has an arcuate notch 126, into which extends a pin 127 fitted in the wall of the piston. To this cup and at the bottom there is secured the lower end of a helically wound bimetallic thermostatic strip 128. The upper end 129 of this strip is secured to the piston, preferably to 10 the top. The tube 117 has a series of ports 130, and the sleeve 122 has ports 131, these ports being adapted to align for flow of air. The air intake is by means of an air duct 132 through the top 104, there being an air tube 133 connected 15 to this duct, and this air tube has a heating coil 134 wound around the exhaust manifold. There is an air chamber 135 between the piston and the cover 104.

The piston is provided with counteracting or 20 counterbalancing springs, there being a lower spring 136 which rests on a washer 137. This washer is connected to a ring 138 on the inside, and on the outside rests on a split ring 139 which fits in an annular groove 140 in the lower end 25 of the cylinder 101. The upper end of the spring bears on the shoulder 141 of the piston. Above the piston there is a second spring 142 which at its lower end bears on the cup 124, and its upper end is seated in a recess 143 in the cap or cover 30 104. It is to be noted that the sleeve 111 is freely rotatable on the lower end of the cylinder 101 and it is provided with a wrench grip head 144 to effect this rotation for a purpose hereinunder detailed. A packing washer 145 fits between the 35 head 144 and the bottom plate 110.

The automatic heating arrangement utilizes a tubular housing designated generally by the numeral 146. This has an upper section 147 providing a relatively large chamber 148, and this 40 has a screw threaded connection 149 with the sleeve 111. A set screw 150 allows clamping together of these parts.

A depending tube 151 is screw threaded and threads into the intake manifold. An end plate 45 152 is secured to the depending portion 151 by pins 153, there being spacers 154. This provides a plurality of radial slots 155 for discharging in the intake manifold. A packing gasket 156 is provided outside of the intake manifold. An electric heating coil 157 has its lower end 158 connected to the closure member 152, this forming a ground connection. To the upper end there is a lead 159 which is connected to an insulated connector 160 which extends through the wall of 50 the upper section 147. An electric lead 161 extends from this connector 160 and to one end 162 of the solenoid coil. The opposite end of this coil has a lead 163 which is illustrated as being connected to a lead 164 from the starting motor 60 switch 19 and the connection 26 of the starting motor 17. Therefore, when the starting motor switch is closed to energize the starting motor, the solenoid is energized and also the heating coil.

The needle valve construction employs a valve 65 seat 165 which is formed in the fixed tube 115 adjacent the lower portion of such tube and through this seat extends the needle point 166 on the stem 167. This stem is connected to a raised center portion 168 of the end plate 152. The needle may be adjusted as to its seat by 70 loosening the set screw 150 and rotating the sleeve 111. As the lower structure 146 is held in a fixed position in the intake manifold and the upper part of the casing having the solenoid is 75

held from rotation by its connection to the fuel supply and auxiliary air supply, the rotation of the sleeve 111 threads the upper part of the housing with the solenoid and the valve seat up and down with reference to the fixed housing 146. An initial adjustment may thus be obtained of the needle valve suitable for different engines.

The manner of operation and functioning of the device of Figs. 5 through 9 is as follows:

- 10 Normally the ports 130 and 131 in the fixed tube 115 and the rotatable sleeve 122, respectively, are in the closed position when the engine is cold, that is, when the thermostatic strip is in the cold condition. This represents the position on starting the cold engine. The piston is supported on the lower spring. This piston has a relatively loose fit in its cylinder so that the needle valve is but partly open. The sleeve 122 has a fairly close sliding fit in the tubular plug 105.
- 15 On closing the starter motor switch the engine is turned over by such starting motor creating a suction in the intake manifold through the carburetor, at the same time the solenoid is energized and elevates the piston 113. This carries the valve seat away from the needle and opens the needle valve. At the same time the heating coil 157 is energized and becomes hot. The suction of the engine quickly draws the liquid fuel upwardly through the pipe 108. This liquid fuel flows downwardly through the tube 115 and past the needle valve where it becomes atomized, and as the liquid fuel is subject to the hot wire coil 157 the drops of liquid fuel are immediately converted into a gas, which gas in expansion forces 20 its way outwardly through the slots 155 into the intake manifold and is carried with the intake air and any generated gas from the carburetor into the engine. The gas is too rich to be combustible by itself but on mixing with the intake air in the intake manifold develops an explosive mixture in the engine. As soon as the engine is started and operating under its fuel, the starting switch is opened, which deenergizes the solenoid and the electric heating coil. In this stage, however, the device will function to meter fuel 25 to the engine. For instance, when the solenoid is deenergized, the piston returns to its normal riding position; this is with the needle valve partly open. With the throttle nearly closed the suction on the piston is greater and pulls this down, closing the needle valve to a greater extent, allowing but little fuel to pass such valve; but when the throttle is opened wide the piston is forced upwardly by the lower spring, thus opening the needle valve to a greater extent and allowing an increased injection of atomized liquid fuel into the intake manifold where it is mixed with the air and fuel vapor from the carburetor.

There is always a certain amount of air suction around the piston, which has a relatively loose fit, so that in all stages of operation there is an air flow through the air intake pipe 133 which has the heating coil 134, and as the air becomes heated, passing around the piston, which heats the thermostatic strip, which functions to obtain a relative rotation of the piston and the sleeve 122 fitting over the tube 115, which action is to open the ports 130 and 131, that is, bringing such ports into registry. In addition, the intake manifold itself becomes heated and the conduction of heat heats the thermostatic strip. Thus, when the engine becomes hot there is an air circulation through the tube 133, the ports 131 and 130, and the slightly opened needle valve.

This connection to atmosphere operates to break the vacuum in the fuel pipe 108 and, hence, no

fuel is drawn upwardly into the auxiliary fuel supply device when the engine is running normally hot. There is, however, a slight additional metered air supply to that in the intake manifold, for when the throttle is nearly closed the suction on the piston maintains the needle valve nearly closed due to the increased vacuum in the intake manifold; but when the throttle is opened the vacuum in the manifold is decreased and the piston elevates, opening the needle valve wider, thus allowing a greater inflow of air which has been preheated by the coil 134. Thus the device operates to function as an air metering device for operating the engine under normal conditions. When it is desired to start the engine 15 while hot, the ports 130 and 131 are open so that on closing the starting motor switch, although the solenoid is energized and the heating coil 157 is also energized, there is no liquid fuel drawn through the auxiliary fuel device but only an 20 additional flow of air.

It is believed obvious that my device may be made as an integral part of a carburetor in both forms. The form of Fig. 2 is illustrated as supported by the carburetor but the form of Fig. 6 25 could also be mounted on the carburetor for direct connection to the intake manifold. It may be advisable in cold climates to connect the heating element with the ignition switch so that the heating coil may be maintained hotter for a 30 longer time. Therefore, in the construction of Fig. 2 the heating coil would be maintained hot until the thermostatic strip opened the circuit. In the construction of Fig. 2 when it is desired to pump additional charges of fuel, the switch 35 controlling the solenoid after being opened may again be closed and this may be done a number of times until the engine is running properly. I find that a suitable diaphragm may be made from fabric which is impregnated with varnish; this 40 withstands the action of the gasoline.

A characteristic of my invention is that the fuel which is initially supplied in the liquid form becomes immediately converted into a gas which is a dry gas, and expands many times the volume 45 of its form in a liquid, and this gas immediately is taken into the intake manifold where it mixes with the air being taken into the engine. Also, the additional hot air supplied with the additional fuel forms a dry gas mixture. Therefore, 50 if the engine does not immediately start but this dry gas is pumped through the engine, it will not condense on account of the fuel being in the dry gas state.

Various changes may be made in the details 55 of construction without departing from the spirit or scope of the invention as defined by the appended claims.

I claim:

1. In the methods of supplying fuel to an engine having an electrically operated auxiliary liquid fuel valve, comprising on starting the engine and by the suction of the engine drawing auxiliary liquid fuel, at the same time sucking an auxiliary air supply into intimate contact with 60 the auxiliary liquid fuel, heating both the auxiliary liquid fuel and air to form a dry gas, introducing such dry gas into the main fuel supply, heating the auxiliary air by the engine heat and after discontinuing the heating of the auxiliary liquid and air, causing the heat of this auxiliary air to stop the flow of the auxiliary air and auxiliary liquid.

2. The methods of supplying auxiliary fuel to an internal combustion engine during the warm- 75

up period, whether the engine is idling or operating at a higher rate of speed which consists in utilizing the suction of the engine to draw a fuel and air mixture of substantially uniform proportions into the engine intake and varying the quantity of mixture supplied in accordance with temperature.

5. The method of supplying auxiliary priming and warm-up fuel to an internal combustion engine having a starting device and a priming pump device, consisting in utilizing the same manual movement to operate both of said devices, thereafter rendering said starting device inoperative,

utilizing engine suction to supply an auxiliary fuel and air mixture of substantially uniform proportions to the engine intake during the warm-up period, heating the auxiliary mixture, and controlling the quantity of auxiliary mixture supplied and the heat applied thereto in accordance with temperature.

6. The method described in claim 3 in which the priming charge initially supplied upon starting the engine is heated for vaporizing the 10 charge.
